COMBINED COSMETIC DISTRIBUTING AND
APPLICATOR DEVICE

Catharine J. Dyer, South Orange, N. J.

Application November 5, 1948, Serial No. 58,536

2 Claims. (Cl. 132—1)

1

This invention relates to improvements in combined distributing and applicator means for cosmetic material.

The invention has for an object to provide a novel means which initially serves as a container or package for use in commercial distribution of cosmetic material, but which, in the hands of the ultimate purchaser or consumer, is adapted to be used so as to facilitate application of the cosmetic material to the person of such purchaser or consumer.

Another object of the invention is to provide a novel card mount adapted to initially serve as a carrier for lip rouge during commercial handling and distribution thereof, said card mount having, integral with its body, a section shaped in outline to conform substantially to the outline of closed lips, and to which a body of lip rouge is affixed; said section being defined by pin perforations or rouletting, whereby the same, with the attached body of lip rouge thereon, may be torn away from the card mount by the ultimate purchaser or consumer, and then folded back upon itself to form a finger piece means by which the user may manipulate the lip rouge for application thereof to the lips; said section when thus torn away from the card mount thereupon leaving in the latter a lip shaped opening adapted to provide a stencil for application by the user to the lips for service as a guide or gauge operative to facilitate application of the lip rouge to the user's lips with assured outline definition.

Other objects of this invention, not at this time more particularly enumerated, will be understood from the following detailed description of the same.

An illustrative embodiment of the invention is shown in the accompanying drawings, in which:

Fig. 1 is a face view of the cosmetic distributing and applicator device in its initial condition for use in commercial distribution of cosmetic material mounted thereon; and Fig. 2 is a side edge elevation view of the same.

Fig. 3 is a face view of the device, showing the detachable lip rouge carrying section being torn away therefrom for use; Fig. 4 is a face view of the torn away lip rouge carrying section; and Fig. 5 shows the lip rouge carrying section folded back upon itself to form finger piece means for holding the lip rouge subject to application to the user's lips.

Fig. 6 is a pictorial view showing the application of the device to the user's lips as a stencil, guide or gauge adapted to facilitate application of the lip rouge to the lips by the user.

in the hereinabove described views, to indicate corresponding parts.

Referring to the drawings, the novel combined cosmetic distributing and applicator device comprises a preferably rectangular body 10 of comparatively stiff sheet material, such e. g. as paper, cardboard, Celluloid or the like. The adjective "stiff" as used herein is intended to mean a degree of stiffness that will enable a sheet of the material of the appropriate size for a card mount or carrier of the class described to stand on edge and thus retain its flat shape when on display; also a degree of stiffness that will cause the removable section hereinafter mentioned to assume a smoothly curved, non-creased form when folded across its center to bring the wing portions into meeting relation. In the upper end portion of said body 10 is formed a removable section 11 which is defined in outline by a surrounding line of pin perforations or rouletting 12. The outline shape of said removable section, as thus defined is that of the closed lips of a human face and therefore of predetermined proportions. Affixed to the front surface of the central portion 13 of said removable section 11 is a body of lip rouge 13, preferably in the form of a stick-like piece or lozenge of suitable shape and projection extent or thickness.

To the front surface of the lower end portion 30 of the body 10 may be attached a powder puff, cleaning pad or similar element 14; the same being affixed in such manner and by suitable means, as e. g. a suitable adhesive, as to be subject to easy separation and removal from the body 10. 35 If the element 14 is of powder puff type it may be charged with a content of face powder, if desired.

In its initial form and condition as above described, and as shown more particularly in Figs. 40 1 and 2, the body 10 is well adapted to serve as a card mount or carrier for the lip rouge and powder puff which is suitable for commercial distribution and handling, and for commercial display on counters or like places of retail sale. 45 Preferably during such distribution, handling and display, the body and its content would be enclosed in a transparent wrapper or envelope. The body in its initial condition as a carrier for commercial purposes also lends itself admirably to 50 distribution by coin controlled dispensing or vending mechanism. It will be obvious that either front or rear faces of the card mount or carrier or both, may be utilized for reception of suitable advertising matter, directions for use, or other desired printed matter.

In the hands of the ultimate purchaser or con-

sumer, the device can be easily and quickly conditioned for use in facilitating application of the lip rouge to the lips of the user. To this end, the user loosens and tears away the removable section 11, which carries the lip rouge 13, from the body 10, thus leaving in said body a lip-shaped opening 15 (see Figs. 3 and 6). After the removable section 11 is thus detached from the body 10, the oppositely extending wings 16 and 17 of said section are rearwardly folded relative to the lip rouge supporting central portion thereof, and said wings are then brought together in rearward extension from the back of said lip rouge supporting central portion (see Fig. 5). The back folded wings 16 and 17 provide a finger piece 18 which may be grasped by the user's fingers, whereby to permit the supported lip rouge 13 to be conveniently manipulated by the user during the operation of applying the lip rouge substance to the user's lips.

The removable lip rouge supporting section 11 having been removed from the body 10, so as to provide in the latter the lip-shaped opening 15, said body is thereupon conditioned for use as a guiding stencil or gauge which is adapted to be applied to the user's mouth preparatory to application of lip rouge to the lips. When, in such use, the body 10 is placed against the user's mouth with the opening 15 opposed to the user's lips, the lips will protrude through said opening so as to be framed by the margins thereof.

By applying the lip rouge 13 to the lips thus exposed through the opening 15 of body 10, said lips may be quickly coated with the lip rouge substance, and application of the coating will be precisely limited to the exposed area of the lips, since the material of the body 10 which surrounds the opening 15 masks areas of the mouth which border the lips, and thus prevents undesired extension of the coating to said latter areas. Furthermore, the margins of the opening 15 serve as guide means adapted to assure definite and precise marginal limits of the coating, and consequently a desired proper shaping of said coating (see Fig. 6).

After or before the application of lip rouge is made, the powder puff, cleaning pad or like element 14 may be removed from the card mount body 10 for use.

While I have shown and described my invention as especially designed for use as a combined distributing and applicator means for cosmetic material, it will be understood that the same, within the broader aspects of my invention, may optionally be used for other materials adapted to be initially carried by the removable section of

the body, and wherein said removable section, when detached from the body, may be arranged to form a finger piece for holding and manipulating the supported material in use.

- 5 Having now described my invention, I claim:
1. A device of the kind described comprising a card mount body of comparatively stiff sheet material having an elongated removable section initially integral with said body, said section being defined by a surrounding line of pin perforations with which said body is provided, a mass of an application material affixed to and supported by said section centrally thereof and being smaller in exposed area than said section, and said section, when detached from the body, being adapted to have the end wings thereof folded back into meeting relation to form a finger piece for holding and manipulating the application material in use.
- 10 2. A device of the kind described comprising a card mount body of comparatively stiff sheet material having an elongated removable section initially integral with said body and of peripheral shape substantially corresponding to the outline of closed lips of the human mouth, said section being defined by a surrounding line of pin perforations with which said body is provided, a mass of lip rouge affixed to and supported by the central portion of said section and being of cross-sectional area less than the area of said section, oppositely extending end portions of said section, when said section is detached from the body, being adapted to have the end wings thereof folded back from the central portion thereof into meeting relation for rearward extension therefrom, whereby to provide a finger piece for holding and manipulating the lip rouge mass in use, removal of said section from the body providing the latter with a stencil opening which substantially conforms to the outline of closed lips of the human mouth.

CATHARINE J. DYER.
